UNITED STATES PATENT OFFICE.

EDWIN R. SAGE, OF JERSEY CITY, NEW JERSEY, ASSIGNOR TO RICHARD S. BROAS, OF EAST ORANGE, NEW JERSEY.

REFRIGERATION APPARATUS.

1,296,012.

Specification of Letters Patent.

Patented Mar. 4, 1919.

Application filed January 21, 1916. Serial No. 73,307.

To all whom it may concern:

Be it known that I, EDWIN R. SAGE, a citizen of the United States, and a resident of Jersey City, county of Hudson, State of New Jersey, have invented certain new and useful Improvements in Refrigeration Apparatus, of which the following is a specification.

This invention relates more particularly to machines operating to produce refrigeration by the alternate liquefaction and evaporation of gases, such, for instance, as ethylchlorid. Of course, any suitable gas which is adapted to be liquefied and then vaporized so as to produce the necessary refrigeration may be used.

My invention is addressed specially to what is known as the high-pressure side of a refrigerating apparatus or system, and is addressed to the manufacture of refrigerating apparatus economically, with the idea of economy not only in manufacture but in space and economy in attention required to operate same.

25 In the drawings in which like numerals represent like parts,

Figure 1 is a side view of a complete refrigerating machine embodying my invention;

30 Fig. 2 is an enlarged longitudinal, sectional view taken through a portion of Fig. 1;

Fig. 3 is an enlarged cross-sectional view on the line A—A of Fig. 1;

35 Fig. 4 is an enlarged section through the expansion valve;

Fig. 5 is an enlarged section through the stuffing box on the rotor shaft;

Fig. 6 is a modification of a portion of 40 Fig. 2; and

Fig. 7 is an enlarged view of the sealing means for the condenser tubes.

Referring to the drawings, 1 is a base upon which is mounted a motor 2. 3 is the 45 rotary compressor shaft connected with the motor shaft by the universal coupling 4. 5 is a stuffing-box. 6 is a rotary compressor consisting of heads 7—7 and cylinder casing 8. 9 is a base or pedestal for the 50 rotary compressor. 10 is a refrigerator supplied by the refrigerant through the pipe 11 which leads from the condensing chamber 18 located within the base 1. 12 is an expansion valve. 13 is an outlet pipe for

the gases leading from the refrigerator 10 55 back to the compressor 6. Located within this pipe is a check valve 14 so as to prevent any back pressure or prevent any change in direction of the current of the gas within the pipe 13. Without this check valve when 60 the electric motor 2 was stopped the rotary compressor would reverse its direction of rotation and tend to force lubricant over into the low-pressure side of the apparatus or system. 15 is a lubricant pipe leading 65 to the stuffing box 5, hereafter explained more in detail. 16 is a water supply pipe to the condenser tubes 19 in the chamber 18. 17 is a water pipe leading from the condenser tubes 19 in the condensing 70 chamber 18 to the water manifold 39 which leads to the water jackets 41 within the compressor heads 7—7. 18 is the condensing chamber located within the base 1. 19—19 are condenser tubes supplied by the 75 water supply pipes 16 and discharged through the discharge pipe 17 which leads to the water jackets on the cylinder heads, as stated above.

This condensing chamber 18 within the 80 base 1 is preferably constructed so that the bottom of it may be used as a reservoir for the lubricant, and also so that it may be used as a reservoir for the liquefied gas. As the specific gravity of the lubricant is 85 greater than that of the liquefied gas the liquefied gas floats on the lubricant. Also located within this chamber 18 is an open pipe 20 having at its top a funnel-shaped flange, 21 which will be explained hereafter. 90

The lubricant pipe 15 leading to the stuffing-box on the rotor shaft 3 extends down through the open pipe 20 to a point below the surface of the lubricant. The point to which this pipe extends near the bottom 95 of the chamber 18 depends upon the quantity of lubricant within the bottom of the chamber—that is, it must extend to a point which will be below the top of the lubricant. 22 is another lubricant pipe which extends to a point near the bottom of the chamber 18 so that its lower end will be submerged within the lubricant. This pipe 22 extends upward through the open pipe 20 to a horizontal passage 23 located within the shell 100 or casing 8 of the compressor. This passage 23 extends from the point at which the pipe 22 connects with it to each of the cyl-

inder heads which are provided with the 5 passages 24—24 (see Fig. 2) which lead into the cylinder so as to lubricate the compressor. This passage 24 leading from the passage 23 is shown in Fig. 2 and in dotted lines in Fig. 3.

Within the base 9 and the lower part of the casing 8 is a separating chamber 25. If 10 desired, the separating chamber may be located wholly within the pedestal 9 or within the casing 8, or within the base 1, it being immaterial to this invention. This separating chamber 25 is provided with a baffle 26 which preferably extends wholly around the chamber obliquely to the sides of the chamber, being so arranged that any lubricant deposited upon the baffle flows toward the center of the separating chamber so as to be fed into the funnel-shaped flange 21 of the 15 open pipe 20, which will act to carry the lubricant down to the bottom of the chamber 8. This open pipe 20 is preferably arranged so that it carries the lubricant below the surface of the lubricating material stored in the 20 bottom of the chamber 18, but, if desired, it may end at a point above the surface of the lubricant. I prefer to construct the apparatus so that the lubricant supply pipes 15 and 22 extend down within the lubricant to 25 a point below the point where the pipe 20 ends within the lubricant, it being arranged in this way so that the lubricant carried to the points of application by the pipes 15 and 22 take the lubricant from that which has 30 been within the bottom of the reservoir rather than drawing the lubricant from open pipe 20, which has just been separated, back to the point of application.

In Fig. 6 I show a modification of the 35 pipes 15 and 22 projecting along the bottom of the reservoir so as to take the lubricant at a removed point from the point where the lubricant flows into the reservoir through the pipe 20. The pipe 15 leads to the stuffing-box 5. This stuffing-box has located within it a series of flexible packing rings 27 made of any suitable material, although I preferably use fibrous material. These packing rings are connected by separators or annular 40 spacers. These packing rings are preferably arranged in series obliquely to the shaft so that the pressure of the fluid in pipe 15 against some of them tends to press the packing rings against the shaft to create a seal to prevent leakage. For instance, the 45 three to the left of the point where the pipe 15 enters the stuffing-box are arranged so that the pressure of the lubricant against these three rings 27 causes them to press 50 against the shaft, while the pressure of the lubricant against the five to the right of the center tends to press the packing rings away from the shaft to permit the flow of lubricant into the rotary compressor. When the 55 rotary compressor is not operating there is a

back pressure against the packing rings 27 which tends to cause a seal to prevent leakage. When the pressure within the pipe 15, or within the rotary compressor falls below atmospheric pressure, the pressure of the atmosphere on the two packing rings 27 to the 70 extreme left of Fig. 5 tends to press same against the shaft to cause a seal, thereby preventing any air from entering the system. Of course, one could use as many packing rings 27 as desired, arranging them in series, as many in each series as desired, and could use any suitable separating means without departing from the spirit of my invention. 75

After the parts have been placed within the stuffing-box it is closed by a gland or cap 28 held in place by a pair of bolts 29 arranged on opposite sides of the stuffing-box, one being shown in Fig. 1. If desired, a 80 spring could be interposed between the gland or cap 28 and the first packing spacer so as to permit the pressure to be kept substantially constant under all running conditions.

Referring to the rotary compressor, 30 is 85 an inlet to the chamber 36. 31 are inlet ports leading from the suction chamber 36 to the compressor chamber 32. The bore of the compressor chamber 32 is arranged so that it is eccentric to the flanges 33 upon which 90 the cylinder heads are mounted and to which the flanges of the cylinder heads 7 are attached. I have found that by constructing this compressor chamber so that its bore is eccentric to the flanges 33, it simplifies the 95 construction of the rotary compressor and obviates possible errors. 34 is the rotor shaft 100 which is arranged concentric to the flanges 33. I preferably construct my compressor so that the point of maximum compression 105 or point of contact is reached in some part of the compressor chamber located at a point below a horizontal line taken through the shaft. The point of contact is generally understood to mean the point of minimum 110 distance between the longitudinal center of the shaft and the cylinder bore. In other words, it is that point where the rotor makes contact with the cylinder bore. 115

35—35 are discharge ports from the compressor chamber. 36—36' are the rotor blades having packing strips 37, 37. These rotor blades are mounted in grooves or guide-ways in the rotor 58 which is keyed to the shaft 34 by the key 59. Pins 38—38 are 120 loosely mounted within the rotor 58 and rotor shaft 34 so that they may pass freely back and forth through same. In Fig. 3 I have shown in dotted lines the opening in the rotor shaft through which the pins pass and have also shown the pins. 39 is the water-inlet manifold which is connected with the pipe 17, the water passing from the manifold into the water-jackets 41, 41 of the cylinder heads on the near side of Fig. 1, 130

and passing out through the manifold 40, which is located on the far side of Fig. 1, and which is shown in Fig. 3. Connected with the manifold 40 is a suitable discharge pipe which leads to any desired place. The liquid refrigerant which is deposited upon the surface of the lubricant within the chamber 18 passes from said chamber through the pipe 11, the lower end of which is located within the chamber 18 so that the lower end or inlet to the pipe is always above the surface of the lubricant, and preferably below the surface of the liquid refrigerant. In other words, the lower end, or inlet to the pipe 11 (Fig. 2) is, under the best working conditions, submerged in the liquid refrigerant. Located at a suitable point on the pipe 11 is the expansion valve 12. Any suitable expansion valve may be used but I prefer the form shown in the drawing or a modified construction of same.

41^a is a valve casing. 41^b is a bonnet held in place by a threaded ring 57. 42 is a passage from the pipe 11 into the main chamber of the valve. At the end of this passage is located a valve seat. 43 is a valve adapted to close the passage 42 when held against the seat. 44 is a circular cam fixedly mounted upon the valve stem 46. 45 is a spring, so arranged that it tends to normally close the passage 42 by forcing the valve 43 against the valve seat. The valve stem 46 is held in a guideway 47, the casing of which guideway acts also as a support for the spring 45. 49 is an arm projecting from the bonnet 41^b on the free end of which is pivotally mounted a bell-crank lever 48 so that one of its arms tends to engage with the cam 44 fixedly mounted on the valve stem 46, while the other arm is in engagement with the pin 50 having an enlarged head 51. 52 is a diaphragm mounted in the top of the valve casing and in constant engagement with the enlarged head 51 of the pin 50. Above the diaphragm is a spring 53 in constant engagement with the diaphragm and so arranged that by rotation of the screw 55 carrying the plunger 54 the pressure of the spring 53 on the diaphragm 52 may be regulated.

Under working conditions the operation of the valve is as follows: Under normal conditions without the apparatus being in operation the screw 55 is operated so that the valve 43 is held against the valve seat to close the passage 42. With the system in operation a vacuum is created on the discharge side of the valve with the result that the atmospheric pressure tends to press the diaphragm downward in opposition to spring 45 thereby withdrawing the valve 43 from its seat through the operation of pin 50, bell-crank lever 48 and flange 44 so as to permit the liquid refrigerant to pass into the valve through the passage 42

and out from the valve through the discharge port to the pipe 11 where it is conveyed to the lower part of the refrigerator 10. If it is desired to open the valve at any time without depending upon the difference in pressure on the opposite sides of the diaphragm the operation of the screw 55 will cause the spring 53 to press downward upon the diaphragm thereby pressing down on the pin 50, the bell-crank lever 48 and the flange 44 in opposition to the spring 45 so as to cause the valve 43 to rise from its seat.

The operation of my apparatus is as follows: The lubricant having been put into the base of the chamber 18 through an inlet which may be located in any suitable place in the base, the gas to be used as a refrigerant, preferably ethylchlorid, is fed in in the usual way on the low-pressure side at any desired point between the expansion valve 12 and the refrigerator 10. The gas having been supplied to the system, the motor 2 is operated, thereby operating the compressor shaft 3 through coupling 4. The gas is drawn in the direction of the arrow (see Fig. 1) from the upper side of the refrigerator through the pipe 13 into the suction chamber 36 of the compressor and through the inlet ports 31 to the compressor chamber 32 where it is compressed and discharged through the ports 35 into the separating chamber where the lubricant is separated from the gas and deposited upon the walls of the chamber and passes down over the baffle (as many baffle plates may be used as desired) into the funnel-shaped flange 21 at the top of the pipe 20, from whence it flows to the refrigerant reservoir at the bottom of the chamber. The compressed gas passes between the baffle 26 and the upper edge of the funnel-shaped flange 21 into the condensing chamber 18, where it comes in contact with the condensing tubes 19-19 and is condensed and drops to the bottom of the condensing chamber where it is stored on the surface of the lubricant. The liquid refrigerant thus deposited upon the surface of the lubricant passes from the chamber 18 through the pipe 11 in which is located the expansion valve 12 where its pressure is reduced, through the balance of the pipe 11 to the refrigerating chamber where it is evaporated and passes out from the upper side of the refrigerator through the gas-pipe 13 which leads back to the compressor. The passing of the liquid refrigerant from the chamber 18 to the refrigerator or evaporator 10 is due to the difference in pressure in the condensing chamber and the refrigerator. The refrigerator or evaporator 10 may be located in a tank in which to manufacture ice, or in a room for refrigerating purposes, or it may be used for any other purpose of refrigeration.

The flow of the lubricant is from the lubricating reservoir at the bottom of the chamber 18 through the pipe 15 to the stuffing-box 5, some of it passing from the stuffing-box into the compressor and then back through the discharge port of the compressor with the compressed gas into the separator and back to the reservoir through means of the baffle 26, flange 21 and pipe 20. The other circuit of the lubricant is from the reservoir to the bottom of the chamber 18 through the pipe 22 into the passage 23, through the outlets 24 where it passes out and is distributed by the rotor 58, its blades 36-36 and packing strips 37, the excess being discharged out through the discharge port 35 into the separating chamber where it is separated and flows back to the reservoir in the same way as described above. For instance, if desired, the chamber 25, shown between the rotary compressor and the condensing chamber 18, could be dispensed with and the rotary compressor mounted on top of the base 1 so as to discharge directly into the condensing chamber 18 and the funnel-shaped opening 21, leading to the pipe 20 which is for the purpose of conveying the lubricant to the lubricant reservoir, would be located below the discharge port and sufficiently large so as to gather all of the lubricant discharged with the gas from the compressor and convey it to the open pipe 20 through which it would flow to the lubricant reservoir.

I have provided means for sealing, against the escape of gas, the opening between the condenser tubes 19 and the tube-sheet or wall 60. At each end of the condenser chamber (see Fig. 7), the tube-sheet or wall 60 is provided with an opening into which the tube 19 is placed. The opening at one end (see Fig. 7) is just sufficiently large to permit the pipe to pass through, while the balance of the opening is of greater area. In the enlarged portion of the opening is provided a screw-thread into which is placed a screw-threaded ferrule or sleeve-nut 61. As shown in Fig. 7, the end of the opening or passage having the reduced area is provided with an annular flange 63 as a result of the manner in which the opening is formed. Of course, if desired, this annular flange 63 could be made separate and attached to the tube-sheet 60 in any desired way. Between this flange 63 and the ferrule 61 I place a packing, preferably a metal packing. The rotation of the screw-threaded ferrule 61 tends to compress this packing 62 between the flange 63 and the end of the screw-threaded ferrule 61, so as to force it against the wall of the opening and the outer surface of the tube 19 to form a gas-tight joint. The tube 19, ferrule 61, tube-sheet 60 and the packing 62 are all preferably made of

metal, although, of course, other suitable material could be used, if desired. These tubes are connected at the ends beyond the tube-sheet 60, as shown in Figs. 2 and 3, so that the liquid flowing in through the pipe 16 (see Fig. 1) enters the end tube in the lower series, passes through that, crosses to the next adjacent tube, back through that tube and crosses to the next adjacent tube, and so until it has passed through all of the tubes in the lower series, and at the end of the last tube in the lower series is provided a passage leading to the last tube in the upper series, the upper series being arranged in the same way so that the liquid, after passing through all of the tubes, flows out through the tube which is above the tube into which the liquid was first introduced. Of course, any other suitable arrangement of the tubes could be provided.

In Fig. 3, I have shown, in dotted lines, the partitions showing how the liquid is caused to flow from one tube to the other in one end of the apparatus. In the other end of the apparatus partitions are similarly arranged, although they are staggered in relation to the arrangement shown in Fig. 3. Changes may, of course, be made in the arrangement of these tubes and in the connections between tubes so that the liquid could be flowing in the same direction in two or more adjacent tubes, if desired.

Many modifications may be made by one skilled in the art without departing from the spirit of my invention.

Having described my invention, what I claim as new and desire to secure by Letters Patent is:—

1. In a refrigerating apparatus, the combination of a base, a condensing chamber within said base, a separating chamber, a passage connecting said separating chamber and said condensing chamber, a compressor, the casing of said separating chamber forming a support for the compressor and a passage connecting said compressor and said separator.

2. In a refrigerating apparatus, the combination of a base, a condensing chamber within said base, a separating chamber, a passage connecting said separating chamber and said condensing chamber, a compressor having a discharge port located below a horizontal line through the compressor shaft, the casing of said separating chamber forming a support for the compressor and a passage connecting said compressor and said separator.

3. In a refrigerating apparatus, the combination of a base, a condensing chamber within said base, a separating chamber, a baffle within said chamber, a passage connecting said separating chamber and said condensing chamber, a compressor, the casing of said separating chamber forming a

support for the compressor and a passage connecting said compressor and said separating chamber.

4. In a refrigerating apparatus, the combination of a base, a condensing chamber within said base, a separating chamber, a baffle within said chamber, a passage connecting said separating chamber and said condensing chamber, a compressor having a discharge port located below a horizontal line through the compressor shaft, the casing of said separating chamber forming a support for the compressor and a passage connecting said compressor and said sepa-
10 rator.

5. In a refrigerating apparatus, the combination of a base, a condensing chamber, a separating chamber, a passage connecting said separating chamber and said condensing chamber, a compressor, the casing of said separating chamber forming a support for the compressor, a lubricant reservoir within said condensing chamber, means for gathering said lubricant and conveying it
20 from said separator to said reservoir, means for conveying said lubricant from said reservoir to the point of application, said last-mentioned means being so arranged that it takes the lubricant from the reservoir at a
25 point removed from the point where the lubricant is fed into the reservoir.

6. In a refrigerating apparatus, the combination of a base, a condensing chamber, a separating chamber, a passage connecting said separating chamber and said condensing chamber, a compressor, the casing of said separating chamber forming a support for the compressor, a lubricant reservoir within said condensing chamber, means for gathering
35 said lubricant and conveying it from said separator to said reservoir, means for conveying said lubricant from said reservoir to the point of application, an outlet for the liquid refrigerant and an expansion valve
40 suitably located on said outlet.

7. In a refrigerating apparatus, a combined base and condenser, a suitable lubri-

cant separator mounted on said base, a compressor, all so arranged that said compressor discharges directly into said separator and 50 said separator discharges compressed gas directly into said condenser and means for carrying the separated lubricant from said separator to a point below the surface of the lubricant held in the lubricant reservoir. 55

8. In a refrigerating apparatus, the combination on the high-pressure side of a rotary compressor having its discharge port below a horizontal line through the shaft, a base for said compressor, a separating chamber located within said base, means for operating the compressor, a condensing chamber located within said base and in direct connection with said separator, a lubricant reservoir in said base, a liquid refrigerant 60 reservoir within said base, means for conveying the lubricant from the separator to a point below the surface of the lubricant within said reservoir, means for taking the lubricant from a point below the surface of 65 the lubricant and conveying it to its point of application, means for taking the liquid refrigerant from a point below the surface of the liquid refrigerant within the liquid refrigerant reservoir and conveying it to 70 any desired point of use, an automatic expansion valve on said last-mentioned means, condensing tubes within said condensing chamber, an inlet to said condensing tubes, an outlet from said condensing tubes, water 80 jackets in the cylinder heads of the rotary compressor and means for conveying the water from said outlet to said water jackets and means for conveying the water from said water jackets. 85

9. In a refrigerating apparatus, a condenser, a compressor, a lubricant reservoir, means separate from the condenser located below the compressor and arranged to gather the lubricant and permit it to pass 90 by gravity to the lubricant reservoir.

In testimony whereof I have signed my name to this specification.

EDWIN R. SAGE.
